UNITED STATES PATENT OFFICE

JULIAN L. PERKINS, OF WEST SPRINGFIELD, MASSACHUSETTS

WRINGER

Application filed April 6, 1931. Serial No. 528,093.

This invention relates to improvements in wringer apparatus and is directed more particularly to wringers of the safety type.

The principal objects of the invention are directed to the provision of a wringer apparatus which incorporates novel features of construction and arrangement of parts whereby the operator may easily and readily disconnect the operating parts so that the operator is safeguarded against personal injury.

Various novel features and advantages of the invention will hereinafter be more fully referred to in connection with the following description of the preferred form of the invention which for purposes of disclosure is shown in the accompanying drawings wherein:

Fig. 1 is a side elevational view of wringer apparatus embodying the novel features of the invention.

Fig. 2 is a longitudinal sectional view through the wringer taken on the line 2—2 of Fig. 6.

Fig. 3 is a plan view of the wringer shown in Fig. 1.

Fig. 4 is a sectional elevational view on the line 4—4 of Fig. 2.

Fig. 5 is a partial end elevational view taken at the left-hand end of the wringer shown in Fig. 1.

Fig. 6 is an end elevational view of the wringer shown in Fig. 1, and taken at the right-hand end thereof, showing the parts in a neutral position, and

Fig. 7 is a similar view showing the parts in an operative position.

Referring now to the drawings in detail the invention will now be fully described.

The wringer may be used with a washing machine or other apparatus and is shown in association with a wringer head H. This head may be supported by a tube 4 depending from the lower side thereof. A drive shaft 6 is journalled in the housing by means of a suitable bearing construction 8 associated with the tube and housing and carries on its upper end a driving pinion 10.

The tube may be supported from a wash-

ing machine or the like and the shaft may be suitably connected to some source of power such as a motor or the like.

A hub or barrel 12 is rotatable and reciprocable in the housing 2 and has a drive shaft 14 journaled therein. Its extreme end 16 is journaled in an outer bearing 18 of the housing. As will be seen the hub 12 and shaft 14 are movable back and forth or longitudinally in the housing and a pair of gears 22 and 24 are fixed to the shaft 14. Accordingly as the shaft 14 is reciprocated in one direction or the other the gears are brought into engagement with the pinion 12.

A guide 30 preferably in the form of a tube is fixed to and extends upwardly from the hub 12 adjacent the housing and a similar guide 32 has a lower bearing portion 34 in which the outer end of the shaft 14 is journaled. Between these guides 30 and 32 and fixed to the shaft 14 is a driving roll 36. It will be noted that the drive shaft 14 is journaled and supported in the housing and that the upper roll is supported and driven thereby. This is to be distinguished from the usual construction where the drive roll shaft is journaled in a frame. In this construction the usual frame is eliminated so that the structure is not only simple in form but is efficient in its operation as well.

Carriers 40 are slidable in the guides 30 and 32 and these have slidable in their upper ends boxes 44. Adjustable plugs 46 in the upper ends of the members 40 are arranged for screwing into and out of said members to vary the tension of springs 48 interposed between the plugs 46 and bottom walls 48 of the boxes 44 so as to yieldingly urge the boxes downwardly of the carriers.

An upper roll 50 is rotatable on a shaft 52 the ends of which are receivable in slots 53 of the boxes. These slots are arranged so that the upper sides thereof bear on the upper sides of the ends of the shaft 52 whereby the springs 48 will urge the boxes downwardly of the carriers and yieldingly hold the roll 50 in contact with the driving roll 56 when the carriers are in a lower position. Slots 51 and 54 in the guides and carriers

permit relative movements of the shaft 52, boxes, carriers and guides.

A collar 60 rotatable around the hub 12 within the housing is movable back and forth therewith and has a rod 62 extending upwardly therefrom which passes through a slot 64 in the upper side of the housing. This slot (as shown in Fig. 3) is angularly disposed and provided with offset portions 65, so as to move the rod back and forth as it is swung along the slot. In this way the hub 12 is moved in one direction or the other to move the shaft and gears 22 and 24 to engage either one of the gears with the pinion 12.

In the rotation of the shaft 6 accordingly as one or the other of the driven gears is meshed with the driving pinion 10, the drive shaft 14 and the roll 36 will be rotated in one direction or the other.

The parts in Figs. 1, 2, 3 and 6 are in neutral position wherein the drive roll shaft is disconnected from the shaft 6.

With the carriers 40 in a lower position the boxes are yieldingly pressed thereby downwardly so that the roll 50 is yieldingly held against the drive roll 36. In the operation of the wringer it is desired in case the operator becomes caught between the rolls that the roll 50 be allowed to move away from the roll 36 to release the pressing action of the upper roll.

The boxes and carriers are releasably held in a lower operating position by means of the following:

Levers 70 are mounted for swinging movements on the hub 12 and bearing 34 at opposite ends of roll 36. Slots 72 of the levers are disposed in a diverging relation (see Figs. 6 and 7) and are connected by a lower slot 73. Pins 74 in the lower ends of the carriers 40 are receivable in said slots.

As shown in Fig. 6, the pins 74 are held by cam portions 75 of the levers 70 to retain the carriers in their lowermost position. In this lower position the springs 48 cause the boxes to be depressed for yieldingly holding the roll 50 in engagement with the roll 36. Should it be necessary to release the roll 50 the levers 70 may be swung in one direction or the other so that the pins may travel upwardly of the slot 72. A lever 70 is shown in releasing position by dot-dash lines in Fig. 7.

To facilitate ready operation of the levers 70 they are connected by bars or rods 80 at opposite sides of the wringer which have their ends fixed in the ends of arms 82 of said levers 70. A longitudinally extending member or members 84 may be fixed to the upper ends of guides 30 and 32, to serve as a hand grip to facilitate tilting of the mechanism. A lock 86 in the form of a ball is urged upwardly by a spring 88 and into engagement with an aperture 90 in the lower side of collar 60 and

tends to hold the collar in its neutral position.

The operator may grasp one of the bars and move it in one direction or the other to thereby swing the lever 70 and release the carriers so that said carriers are free to move upwardly of the guides. In the event that an operator should catch a hand or clothing between the bite of the rolls, the levers 70 may be instantly swung in one direction or the other, the upper roll is relieved of spring pressure and in this way the operator is safeguarded against injury.

As has been stated, the parts are shown in Figs. 1, 2, 3, and 6 in a neutral position wherein the driving shaft 14 is disconnected from the drive shaft 6, but in the operation of the wringer the parts will be tilted in one direction or the other or to such a position as shown in Fig. 7.

The neutral position may be called a safety position because in this position the driving and driven gears cannot be operatively connected. When the wringer is swung to a tilted position however the gears may be connected for the roll driving operation and in a tilted position the upper roll is releasably held in contact with the lower roll.

A lug 80 of the guide adjacent the housing has a part 82 which projects over on to the housing and this is receivable in a transverse slot between projections 84 on the upper side of the housing. In a neutral position the lug 82 lies within the slot between the projections so that the wringer parts are held against reciprocating movements to engage the gears.

When it is desired to tilt the wringer for operation it may be tilted in one direction or the other from the neutral position so that the lug 82 may pass back and forth in longitudinal slots 87 between opposite sides of the member 84 and the inner sides of members 88 carried on the upper side of the housing. The ends of these lugs 88 act as stops also to limit the tilting movements of the wringer in one direction or the other.

It will be assumed that it is desired for operation to tilt the wringer to the position shown in Fig. 7. In this case the wringer is tilted rearwardly so that the lug 82 abuts the inner end of lug 88. Now the wringer may be moved back and forth, and the rod 62 may be moved along the slot 64 in either direction to cause either of the gears 22 or 24 to be meshed with the driving gear 10. With the parts in neutral position the rod 62 may not be moved relative to slot 64 because the member 60 is held against axial movements.

With one of the driven gears in mesh with the driving gear the shaft 14 is rotated. In order to releasably hold the upper roll 50 in yielding engagement with the lower drive roll 36 the levers 70 are swung so that the pins 74 of the carrier are within the slots 73 of the levers.

Clothes are passed by the operator through

the bite of the wringer rolls for instance in the direction of the arrow F. In case it is desired or necessary to release the upper roll the operator has merely to contact with one of the levers 70 or a rod 80 connecting the same to effect swinging movements thereof. As shown in Fig. 7, when the levers 70 are swung to the dot-dash position the pins 74 pass upwardly in slots 72 thereof so that the roll 50 is free to be elevated by reason of anything which may be between the rolls 36 and 50.

For instance, if an operator has a hand caught between the rolls as soon as the lever 70 is moved the hand will cause the roll 50 to be elevated thereby, and in that way the hand is relieved of the pressure and the operator is guarded against injury.

In any operative position the upper roll is yieldingly held against the lower roll by reason of the springs 48. For the safety feature the spring mounting for the yielding pressure is not relied on, but rather the parts in which the spring mounting is carried are releasable by the operator so that the roll 50 is freely movable away from the roll 36.

Various changes may be made in the form of the apparatus without departing from the spirit and scope of the invention and it is therefore desired to be limited by the appended claims rather than by the foregoing description.

What is claimed is:

1. A wringer comprising in combination, a support, a barrel rotatable and reciprocable therein, a shaft rotatable in said barrel having a free end extending from said support, engageable driven and driving gears associated with said shaft and support, movable means associated with said barrel and support and movable on said barrel to facilitate reciprocation of said barrel for moving said gears between neutral and operative positions, roll supporting means associated with said support and shaft, coacting wringer rolls associated with said shaft and said roll supporting means and means associated with said barrel and support to releasably hold said barrel against movement.

2. A wringer comprising in combination, a housing having a barrel reciprocable and oscillatable therein, a shaft journalled in said barrel carrying driven gears for alternately engaging a driving pinion in said housing and being reciprocable with said barrel, a member rotatable on said barrel having a projection in engagement with a cam on said housing whereby the barrel is reciprocated by rotation thereof to move said gears into and out of engagement with said pinion, a part associated with said barrel for releasably engaging a part on said housing for holding said barrel against reciprocation, guides associated with said barrel and an outer end of said shaft, means associated with said guides to restrain them against rotation with said shaft,

a driving roll on said shaft between said guides and a driven roll having a shaft associated with said guides.

3. A wringer comprising in combination, a housing having a barrel reciprocable and oscillatable therein, a shaft journalled in said barrel carrying driven gears for alternately engaging a driving pinion in said housing and being reciprocable with said barrel, a member rotatable on said barrel having a projection in engagement with a cam on said housing whereby the barrel is reciprocated by rotation thereof to move said gears into and out of engagement with said pinion, a part associated with said barrel for releasably engaging a part on said housing for holding said barrel against reciprocation, guides associated with said barrel and an outer end of said shaft, means associated with said guides to restrain them against rotation with said shaft, a driving roll on said shaft between said guides and a driven roll having a shaft associated with said guides and means for releasably holding said driven roll in yielding engagement with said driving roll.

4. A wringer comprising in combination, a housing having a barrel reciprocable and oscillatable therein, a shaft journalled in said barrel carrying driven gears for alternately engaging a driving pinion in said housing and being reciprocable with said barrel, a member rotatable on said barrel having a projection in engagement with a cam on said housing whereby the barrel is reciprocated by rotation thereof to move said gears into and out of engagement with said pinion, a lug associated with said barrel for releasably engaging a lock on said housing for holding said barrel against reciprocation, guides associated with said barrel and an outer end of said shaft, means associated with said guides to restrain them against rotation with said shaft, a driving roll on said shaft between said guides and a driven roll having a shaft associated with said guides, the said guides including members slidably relative thereto which receive opposite ends of said roll shaft.

5. A wringer comprising in combination, a housing having a barrel reciprocable and oscillatable therein, a shaft journalled in said barrel carrying driven gears for alternately engaging a driving pinion in said housing and being reciprocable with said barrel, a member rotatable on said barrel having a part in engagement with a part on said housing whereby the barrel is reciprocated by rotation thereof to move said gears into and out of engagement with said pinion, a part associated with said barrel for releasably engaging a part on said housing for holding said barrel against reciprocation, guides associated with said barrel and an outer end of said shaft, means associated with said guides to restrain them against rotation with said shaft, a driving roll on said shaft between

said guides and a driven roll having a shaft associated with said guides, the said guides including members slidale relative thereto in which the ends of said roll shaft are yieldingly mounted.

6. A wringer comprising in combination, a housing having a barrel reciprocable and oscillatable therein, a shaft journalled in said barrel carrying driven gears for alternately 10 engaging a driving pinion in said housing and being reciprocable with said barrel, a member rotatable on said barrel having a part in engagement with a part on said housing whereby the barrel is reciprocated by rotation thereof to move said gears into and out 15 of engagement with said pinion, a part associated with said barrel for releasably engaging a part on said housing for holding said barrel against reciprocation, guides associated with said barrel and an outer end of said shaft, means associated with said guides to restrain them against rotation with said shaft, a driving roll on said shaft between said guides and a driven roll having a shaft associated with said guides, the said guides including relatively slidale carriers having relatively slidale boxes which receive opposite ends of said roll shaft.

7. A wringer comprising in combination, a 30 housing having a barrel reciprocable and oscillatable therein; a shaft journalled in said barrel carrying driven gears for alternately engaging a driving pinion in said housing and being reciprocable with said barrel, a member rotatable on said barrel having a part in engagement with a cam on said housing wherein the barrel is reciprocated by rotation thereof to move said gears into and out 35 of engagement with said pinion, a part associated with said barrel for releasably engaging a part on said housing for holding said barrel against reciprocation, guides associated with said barrel and an outer end of said shaft, means associated with said guides to restrain them against rotation with said shaft, a driving roll on said shaft between said guides and a driven roll having a shaft associated with said guides, the said guides including relatively slidale carriers having relatively slidale boxes which receive opposite ends of said roll shaft and springs between opposite ends of said carriers and boxes.

8. A wringer comprising in combination, a 55 housing having a barrel reciprocable and oscillatable therein, a shaft journalled in said barrel carrying driven gears for alternately engaging a driving pinion in said housing and being reciprocable with said barrel, a member rotatable on said barrel having a projection in engagement with a cam on said housing whereby the barrel is reciprocated by rotation thereof to move said gears into 60 and out of engagement with said pinion, a

part associated with said barrel for releasably engaging a part on said housing for holding said barrel against reciprocation, guides associated with said barrel and an outer end of said shaft, means associated with said guides to restrain them against rotation with said shaft, a driving roll on said shaft between said guides and a driven roll having a shaft associated with said guides, the said guides including members slidale relative thereto in which the ends of said roll shaft are yieldingly mounted and means for releasably holding said carriers in an operative position.

9. A wringer comprising in combination, a 80 housing having a barrel reciprocable and oscillatable therein, a shaft journalled in said barrel carrying driven gears for alternately engaging a driving pinion in said housing and being reciprocable with said barrel, a member rotatable on said barrel having a projection in engagement with a cam on said housing whereby the barrel is reciprocated by rotation thereof to move said gears into and out of engagement with said pinion, a part associated with said barrel for releasably engaging a part on said housing for holding said barrel against reciprocation, guides associated with said barrel and an outer end of said shaft, means associated with said guides to restrain them against rotation with said shaft, a driving roll on said shaft between said guides and a driven roll having a shaft associated with said guides, the said guides including members slidale relative thereto in which the ends of said roll shaft are yieldingly mounted and means for releasably holding said carriers in an operative position and means for manual engagement to operate said holding means.

10. A wringer comprising in combination, a support, a member reciprocable and rotatable therein between operative and inoperative position, a guide associated therewith, a shaft extending from said support having a free end, a guide associated therewith, means associated with said guide and support to hold the said guides against rotation with said shaft, wringer rolls associated with said shaft and guides, a driving element associated with said support and a driven element associated with said shaft and member reciprocable therewith to engage said driving element, the said support being provided with intercommunicating longitudinal and transverse slots for receiving a projection associated with said first named guide whereby the said guide and member are held against reciprocation when in inoperative position.

11. A wringer comprising in combination, a support, a member reciprocable and rotatable therein between operative and inoperative position, a guide associated therewith, a shaft extending from said support having

- a free end, a guide associated therewith, means associated with said guide and support to hold the said guides against rotation with said shaft, wringer rolls associated with said shaft and guides, a driving element associated with said support and a driven element associated with said shaft and member reciprocable therewith to engage said driving element, the said support being provided with a transverse slot and a stop in spaced relation at the end thereof whereby the guide and member are held against reciprocation when in inoperative position and are allowed to reciprocate when in operative position.
12. A wringer comprising in combination, a support, a member reciprocable and rotatable therein between operative and inoperative position, a guide associated therewith, a shaft extending from said support having a free end, a guide associated therewith, means associated with said guide and support to hold the said guides against rotation with said shaft, wringer rolls associated with said shaft and guides, a driving element associated with said support and a driven element associated with said shaft and member reciprocable therewith to engage said driving element, the support being provided with a slot disposed transversely to the axis of oscillation of said member and a longitudinal slot and a projection on said guide receivable in said slots all adapted and arranged whereby the said member is held against reciprocation when the guide is in inoperative position and permitting reciprocation thereof when the guide is in operative position.
13. A wringer comprising in combination, a support, a member reciprocable and rotatable therein between operative and inoperative positions, a guide associated therewith, a shaft extending from said support having a free end, a guide associated therewith, means associated with said guide and support to hold the said guides against rotation with said shaft, wringer rolls associated with said shaft and guides, a driving element associated with said support and a driven element associated with said shaft and member reciprocable in said support with said first-named member, and means associated with said second-named member to effect relative reciprocating movements thereof as they are relatively oscillated.
14. A wringer comprising in combination, a support, a member reciprocable and rotatable therein between operative and inoperative positions, a guide associated therewith, a shaft extending from said support having a free end, a guide associated therewith, means associated with said guide and support to hold the said guides against rotation with said shaft, wringer rolls associated with said shaft and guides, a driving element associated with said support and a driven element associated with said shaft and member reciprocable therewith to engage said driving element, the support being provided with a slot disposed transversely to the axis of oscillation of said member and a longitudinal slot and a projection on said guide receivable in said slots all adapted and arranged whereby the said member is held against reciprocation when the guide is in inoperative position and permitting reciprocation thereof when the guide is in operative position.
15. A wringer comprising in combination, a support, a member reciprocable and rotatable therein between operative and inoperative positions, a guide associated therewith having a lug, a shaft extending from said support having a free end, a guide associated therewith, means associated with said guide and support to hold the said guides against rotation with said shaft, wringer rolls associated with said shaft and guides, a driving element associated with said support and a driven element associated with said shaft and member reciprocable in said support with said first-named member, and means associated with said second-named member to effect relative reciprocating movements thereof as they are relatively oscillated.
16. A wringer comprising in combination, a support, a driving member, a driven shaft extending from said support having a driven member for engaging said driving member, an oscillatable and reciprocable member movable between operative and inoperative positions for engaging and disengaging said driving and driven members, spaced parts associated with said member and shaft and connection between said member and support to hold said parts against rotation with said shaft, coacting rolls between said parts and means associated with said support and one of said parts to hold said member against reciprocating movements when in inoperative position.
17. A wringer comprising in combination, a support, a driving member, a driven shaft

extending from said support having a driven member for engaging said driving member, an oscillatable and reciprocable member movable between operative and inoperative positions for engaging and disengaging said driving and driven members, spaced parts associated with said member and shaft and connections between said member and support to hold said parts against rotation with said shaft, coacting rolls between said parts and means associated with said support and one of said parts to hold said member against reciprocating movements when in inoperative position and yielding means to hold said member in inoperative position.

In testimony whereof I affix my signature.
